202,983

UTILITY POCKET FOR AUTOMOBILE DOOR

Perry E. Allen, 5644 Round Hill Road,
Birmingham, Mich.

Filed Oct. 6, 1964, Ser. No. 82,050

Term of patent 3½ years

(Cl. D14—6)

FIG. 1

FIG. 2

FIG. 3

FIG. 1 is a top plan view of a utility pocket for automobile door, embodying my new design.

FIG. 2 is a front elevational view thereof.

FIG. 3 is a left side elevational view thereof.

I claim:

The ornamental design for a utility pocket for automobile door, as shown.
